DESIGN FOR A FACE GUARD FOR SEWING MACHINE OPERATORS

Jonas F. Imberman, Los Angeles, Calif.

Application February 24, 1945, Serial No. 118,131

Term of patent 14 years

(Cl. D70—2)

To all whom it may concern:

Be it known that I, Jonas F. Imberman, a citizen of the United States, residing at 738 South Spaulding Ave., Los Angeles, in the county of Los Angeles, State of California, have invented a new and ornamental Design for Face Guard for Sewing Machine Operators, of which the following is a specification, reference being had to the accompanying drawing, forming part thereof.

Fig. 1 is a front view of a face guard for sewing machine operators, showing my new design;

Fig. 2 is a side view thereof;
Fig. 3 is a view of the opposite from that shown in Fig. 2; and

Fig. 4 is a bottom plan view thereof.

I claim:

The ornamental design for a face guard for sewing machine operators, as shown.

JONAS F. IMBERMAN.
